MACHINE FOR REPAIRING KNITTED FABRICS

Application filed May 11, 1929. Serial No. 362,386.

The invention relates to a machine and method for repairing rips or runs in knitted fabrics, particularly knitted stockings.

The object of the present invention is to provide a simple, practical and efficient fabric or stocking repairing machine of strong, durable and comparatively inexpensive construction designed particularly for mending the ladder-like runs in silk stockings and equipped with a power actuated needle for looping the threads of a run and means cooperating with the needle for enabling the stocking to be repaired to be stretched in repair position and to be held at opposite sides of the slot by the hands of the operator and to have the tension of the threads of the stocking controlled by the operator and the successive threads of the run fed to the needle without the hands of the operator releasing their grip on the fabric, whereby the stretching of the stocking, the tensioning of the threads thereof, and the feeding of the stocking to the needle, may be simultaneously performed by hand.

A further object of the invention is to provide a machine of this character which will possess all the advantages of a power actuated machine in the operation of the needle and all of the advantages of hand manipulation of an expert operator in stretching the stocking and tensioning the threads thereof and feeding the same to the needle so that the stretching or tensioning and the feeding may be adapted to the particular character of the stocking to be repaired, whereby stockings having the finest threads as well as stockings having the heavier threads may be repaired without liability of breaking the threads or otherwise injuring the stockings.

A further object of the present invention is to equip the machine with means for adjusting the needle bar vertically to raise and lower the same independently of the needle reciprocating mechanism to change the position of the needle with respect to the said mechanism to accommodate different types of needles.

A further object of the invention is to provide a cam mechanism for reciprocating

the needle to enable the speed of the needle to be controlled and varied when necessary during the reciprocation thereof to adapt the machine to the particular type of needle employed and the specific character of the thread looping operation thereof, as well as to adapt the operation of the needle to hand fed fabrics.

Another object of the invention is to provide illuminating means arranged interiorly of the machine and adapted to project rays of light through the slot of the fabric supporting form to light up the threads of a run so that the cross threads will stand out distinctly and show clearly to the operator the threads to be fed to the needle.

Another object of the present invention resides in the provisions of a machine or method for mending runs in fabrics equipped with a power actuated needle for looping the threads of a run and with which is adapted to cooperate a manually operable slideable fabric supporting form which may be operated by hand at the will of the operator for the purpose of feeding the threads of a run successively to the power actuated needle, and thereby effect a closing of the run.

Another object resides in the provision of a machine for mending runs in fabrics equipped with means for manipulating the threads of the run to close the latter, such means cooperating with means to support the fabric, one of the said means being arranged in a predetermined definite position and the other means being slideable by hand at the will of the operator relative to the said means located in definite position so as to permit the threads of the run to be successively presented to the means for closing the run.

With these and other objects in view, the invention consists in the construction and novel combination and arrangement of parts hereinafter described, illustrated in the accompanying drawings, and set forth in the claims hereto appended, it being understood that various changes in the form, proportion, and minor details of construction, within the scope of the claims, may be

resorted to without departing from the spirit of the invention or sacrificing any of the advantages thereof.

In the drawings:

Fig. 1 is a side elevation of a stocking repairing machine constructed in accordance with this invention.

Fig. 2 is a central longitudinal sectional view of the same, partly in elevation.

Fig. 3 is a transverse sectional view of the stocking repairing machine taken substantially on the line 3—3 of Fig. 2.

Fig. 4 is a horizontal view of the same taken substantially on the line 4—4 of Fig. 2.

Fig. 5 is a similar view taken substantially on the line 5—5 of Fig. 2.

Fig. 6 is a detail sectional view illustrating the manner of mounting the needle.

Fig. 7 is a detail transverse sectional view illustrating another form of friction surface for holding the fabric.

Fig. 8 is a detail perspective view of the rear portion of the stocking holding form.

Fig. 9 is a detail edge view of one of the horizontal form supporting bars, partly in section.

Fig. 10 is a side elevation of the same.

Fig. 11 is a detail plan view of the stocking holding lever.

Fig. 12 is a detail side view thereof.

In the accompanying drawings, in which is illustrated the preferred embodiment of the invention, the stocking repairing machine comprises in its construction a single vertically movable needle bar 1 adjustably held in a vertically reciprocating needle bar carrier 1^a mounted in a hollow head 2 of a tubular or hollow arm 3 of a suitable frame 4 which may be constructed of any desired material, and which can be mounted upon a table or other support (not shown) in any suitable manner, as will be readily understood. The frame 4 is preferably provided at the base with a rear transverse rib 4^a which is rounded at the lower face, as clearly illustrated in Fig. 1 of the drawings, to form a fulcrum on which the frame is adapted to be tilted to raise and lower the front portion of the frame. The frame is secured in such pivotal adjustment by means of spaced adjusting screws 4^b mounted in threaded openings 4^c in the front portion of the base of the frame and provided with knurled heads and equipped with locking nuts 4^d which clamp the upper face of the front portion of the base, as clearly illustrated in Fig. 2 of the drawings. The spaced vertical adjusting screws 4^b and the rear transverse rib form a firm support for the frame, so that there will be no liability of accidental lateral tilting of the machine. Any other suitable means may, of course, be provided for adjusting the machine and for securing the same in its adjustment.

The head 2 is provided at the top and bottom with vertically aligned guide openings 2^a through which the needle bar carrier slides, and the said needle bar is equipped at its lower end with a needle 5 detachably secured in a socket in the lower end of the needle bar by a set screw 6. In practice, the head 2 is of a sectional character to enable the parts to be readily assembled. The needle bar carrier 1^a consists of a tube or sleeve in which the needle bar 1 is adjustably held by an adjusting screw 1^b mounted in a threaded socket 1^c in an enlargement of the upper end of the needle bar carrier and having a knurled head 1^d which engages a groove 1^e in the adjacent side of the upper end of the needle bar 1, as clearly illustrated in Fig. 6. The screw is adapted to be rotated to raise and lower the needle bar 1 with respect to the needle bar carrier, to position the needle properly with relation to the work. By rotating the adjusting screw 1^b the needle may be raised or lowered relatively to the needle bar carrier 1^a. This will enable the vertically reciprocating needle bar to be adjusted to accommodate different kinds of needles and to permit the latter to be used in the stocking repairing machine.

The needle bar carrier is provided with a horizontal arm 7, preferably formed integral with a collar 7^a which is interiorly threaded and engages an exteriorly threaded portion of the needle bar carrier, as indicated at 7^b, the collar being preferably held against accidental rotary movement by a stop 7^c mounted in a threaded perforation of the collar 7^a. The arm 7 is engaged by a coiled spring 8 for yieldably urging and moving the needle bar downwardly, and the spring 8 is arranged on an adjusting screw 9 and is interposed between the arm 7 and the upper wall of the chamber of the hollow head. The adjusting screw 9, which is threaded into the top of the hollow head at 10, extends through an opening 10^a in the horizontal arm 7 and is adapted to position a collar or head 11 at the proper elevation for limiting the downward movement of the needle by forming a stop for the said arm 7. The collar or head 11, which is preferably secured on a reduced terminal portion of the screw 9 by a pin 12 or other suitable fastening device, forms a stop or abutment for the arm 7 of the needle bar carrier, to limit the downward movement of the needle bar, the coiled spring forcing the needle bar to the limited position in its downward movement; and the arrangement of the adjusting screw in the opening of the said arm 7 provides a guide for the arm and the needle bar carrier to prevent any rotary movement of the same in the bearings of the head 2 of the hollow arm 3. While the needle bar carrier is illustrated in the accompanying

drawings as being of tubular or cylindrical formation, it may be of any other desired form, and the vertically adjustable needle bar 1 may be of any desired configuration 5 in horizontal section.

The needle, needle bar, and needle bar carrier are positively moved upwardly by means of a cam actuated lever 13 fulcrumed intermediate of its ends at the rear end of

- 10 the hollow arm 3 of the frame of the machine on a transverse pin or pivot 14 to form front and rear arms. The front arm of the lever extends to the needle bar carrier and is provided at its front end with an anti-friction roller 15 which bears against the lower face of the horizontally projecting arm 7. The anti-friction roller 15 is mounted on a suitable pin or pivot 16 projecting laterally from the inner side of the lever 13, as clearly illustrated in Fig. 3 of the drawings. When the front arm of the lever is swung upwardly by means hereinafter described, the needle bar carrier will be positively raised, and when the front arm 25 of the lever 13 swings downwardly will be moved downwardly by the coiled spring 8.

The rear arm of the lever 13 is arranged at an obtuse angle to the front arm of the said lever, and is provided with a roller 19

- 30 which operates in a groove 20 of a cam 21 keyed or otherwise fixed to a transverse shaft 22. The transverse shaft 22 is journaled in suitable bearings 23 and 24 in the sides of the frame of the machine, and it is 35 extended beyond one side of the frame, and is equipped with a hand wheel 25 and a grooved pulley 26 keyed or otherwise secured to the shaft 22 and preferably formed integral with each other, or they may be 40 formed in any other desired manner and be fixed to the shaft in any suitable way. The grooved pulley 26 is connected by a belt 27 with a grooved pulley 28 of the power shaft 29 of an electric motor 30, preferably secured to the frame of the machine at the 45 back thereof, as illustrated in Figs. 1 and 3 of the drawings, but the motor may be mounted in any other desired position on the frame, as will be readily understood.

- 50 When the shaft 22 is rotated by the motor 30, the cam 21 will be rotated and the lever 13 will be oscillated. When the front arm of the lever 13 moves upwardly it will lift the needle bar and the spring 8 will move 55 the needle bar downwardly during the downward movement of the front arm of lever 13. In practice, the speed of the motor will be controlled by a suitable treadle-operated rheostat, so that the treadle and the needle 60 will be reciprocated vertically at the desired speed.

The needle is provided at its lower end with a hook 31 which has a swinging latch 32 pivoted at 33 above the hook as shown in 65 Fig. 6. When the pivoted latch 32 is opened

it exposes the hook 31, and when the latch is closed it covers the throat or opening leading into the hook and forms an eye. The last perfect loop of the stocking at the run or rip is placed in the hook 31, and as the 70 needle descends the loop slides upwardly on the shank of the needle, opening the latch and moving upward on the needle until the latch is released. When the latch is released, it drops by gravity and falls over the next 75 cross thread of the run in the stocking. The loop remains on the shank of the needle, and as the needle rises the hook catches the said thread and the latch closes over the hook forming an eye and encasing or enclosing 80 and confining the thread in the eye of the needle. The thread is then pulled up through said loop, forming another loop, and this process is continued until all of the cross threads are looped back into the fabric. 85

It will be understood that, while but one type or construction of needle is illustrated in the accompanying drawings, the invention is not limited to any particular type of needle, and various forms of needles may be 90 employed.

The fabric or stocking to be repaired is arranged on a slidable form 34 arranged in substantially a horizontal position and consisting of a hollow or tubular member substantially oblong in cross section and provided with a tapered front portion 35, the taper being formed by the upward curving or inclination of the bottom of the tubular member at the front thereof, as illustrated 95 in Figs. 1 and 2 of the drawings. The top of the tubular member is substantially flat and is provided with a central longitudinal slot 36 to provide a passage for the needle 5, and it has friction surfaces at opposite sides 100 of the slot 36. The friction surfaces 37 at opposite sides of the said slot 36 are formed by fine ribs and intervening grooves, which are adapted to prevent the fabric from slipping and which enables the fabric to 105 be held in proper position with the cross threads of a run arranged in properly manually tensioned spaced relation so as to be fed to and successively operated on by the needle. A relatively large portion of the 110 fabric or stocking to be repaired may be stretched over the form and held at opposite sides of the needle slot by the operator, and is fed by hand to the needle by sliding the form inwardly or rearwardly. This 115 permits the fabric to be held by the operator at each side of the needle, and to be fed simultaneously to the needle without the operator releasing the grip of the hands on the stocking. By this means, the stocking 120 to be repaired may be manipulated by an expert operator with all of the advantages of hand repairing, in that the stocking may be stretched and arranged to suit the character of the material, without injuring the 125 130

most delicate fabrics, and at the same time all of the advantages of a power operated machine are obtained through the vertical reciprocation of the power operated needle.

5 The friction surfaces at opposite sides of the slot 36 are of a width less than the width of the top of the form, which is provided with smooth side portions to enable it to be conveniently grasped and held by the operator. The form is provided at opposite sides with longitudinal guide grooves 38, and it is supported and guided by means of anti-friction rollers 39 and 40 mounted on horizontal form supporting bars or plates 41 and 15 bearing against the grooves 38 of the form at the top and bottom walls of the said grooves. The rolls 39 bear against the top walls of the grooves 38, and the rollers 40 bear against the lower walls thereof. The 20 rollers are mounted on suitable pins or pivots which are preferably in the form of screws 42 having heads countersunk in the anti-friction rollers, and the threaded portions of the screws engage threaded openings in the bars 41. The front ends 43 of the horizontal form supporting bars are bent inwardly at right angles and extend into the grooves 38, as clearly illustrated in Fig. 4 of the drawings to prevent the stockings 30 from catching on the ends of the supporting bars. The form supporting bars are suitably secured to the sides of the frame 4 in grooves 44 formed in the inner faces of the sides of the frame, as clearly illustrated in 35 Fig. 3 of the drawings. The slidable form, which may be of sufficient length to accommodate a relatively large portion of a stocking, is adapted to extend through an opening 45 in the back of the frame of the machine, and the rear end of the tubular form is closed by a plug or plate 46, recessed at its edges to fit within the form and to provide marginal flanges 47 which abut against the rear end edges of the said form. The plug 45 or closure plate is secured to the rear end of the form by means of screws 48 or other suitable fastening devices.

The said plug or plate 46 supports a tube 49 arranged within the form and threaded 50 at its rear end 50 in an opening 51 in the closure plate or plug 46 and carrying an electric light socket 52 at its inner or front end. The electric light socket is adapted to receive an electric light bulb or lamp 53 to 55 in the ordinary manner, to provide an interior illumination, so that the operator will have light from the inside of the form, showing clearly the runs to be mended. The tube 49, which is constructed of metal 60 or other suitable material, forms a conduit for an electric cord 54. The closure plug 46 carries the electric light and is adapted to be readily removed for removal of the electric light when required.

65 In practice, the operator pulls the form

forward or outward and stretches the stocking over it and arranges the run on the friction surface. The grooves and ribs of the friction surface do not correspond to the number of cross threads in a stocking, but 70 are arranged so as to permit the threads of a run to be placed on the form according to the best judgment of the operator. Before placing the stocking on the form, the operator presses down on a foot treadle (not 75 shown) which pulls down a rod 55 connected at its upper end at 56 to the rear arm of a lever 57 fulcrumed intermediate of its ends on a transverse shaft 58 at one side of the frame of the machine and angularly 80 bent intermediate of its ends to provide an intermediate angularly disposed portion 57^a which arranges the front portion of the lever 57 centrally of the machine and in the plane of the longitudinal slot 36 of the stocking 85 supporting form. The front end of the lever 57 carries a stocking engaging foot 59 and feed disks or rolls 60 located at opposite sides of the front portion of the lever 57 slightly in rear of the foot.

90 The foot 59 has spaced side portions which bear upon the fabric of the stocking at opposite sides of the slot 36, and the needle, for holding the fabric in position while the cross threads of a run are being manipulated by the needle to close the run. The pair of rolls or disks 60 which are mounted on a suitable shaft or pivot 61, operate to assist in holding the stocking in proper position while feeding the stocking or other fabric to 100 the needle through the inward or rearward sliding movement of the form. The feed disks or rolls are provided at their peripheries with friction surfaces 62 preferably formed by fine transverse ribs and intervening grooves and adapted to cooperate with the friction surfaces of the form and with the foot in guiding the work and holding the same on the form.

105 The foot, which has spaced side portions, 110 operates at opposite sides of the longitudinal slot 36 of the form and is provided with an attaching shank 63 secured to the front end of the lever 57. The lever 57 is arranged exteriorly of the frame of the machine, and 115 when it is desired to hold the foot 59 and the feed roll 60 elevated, the rear arm of the lever is depressed and engaged by a cam 64 mounted on one side of the frame on an eccentric pivot 65 which is preferably in the 120 form of a screw. The cam is provided with a suitable operating member 64^a projecting horizontally from the cam and arranged eccentrically thereof to enable the cam to be readily rotated on the pivot 65.

125 The needle bar is also adapted to be held in an elevated position by means of a manually operable device consisting of a horizontal shaft or pivot 66 having fixed to its outer end an operating handle or arm 67 and

carrying at its inner end an arm 67^a, which is adapted to be swung upwardly into a supporting position beneath the projecting portion 7 of the needle bar carrier. The arm 67^a is adapted, as illustrated in Fig. 2 of the drawings, to be arranged in a horizontal position out of contact with the projecting portion 7 of the needle bar carrier, and is also adapted to be swung upwardly to a vertical position into the path of the said portion 7 for limiting the downward movement thereof to hold the needle bar carrier and the needle in an elevated position out of contact with the material. By means of the cam 64 and the said manually operable device, the guide foot and feed rolls and the needle may be supported in elevated position while the stocking to be repaired is being placed on the stocking receiving form in proper position to be operated on by the needle.

The slideable form is limited in its sliding movement by a stop consisting of a lug 68 projecting upwardly from a plate 69 secured to the frame at the front portion thereof at a point beneath the slideable form. The slideable form is provided in its bottom with a longitudinal slot 70 into which the lug 68 extends, and the rear wall of the slot 70 is adapted to abut against the lug 68 to limit the outward or forward movement of the form, while the front wall of the slot 70 is adapted to abut against the lug 68 to limit the inward or rearward movement of the form. The plate 69 is detachably secured to the frame of the machine by a screw 71 and is adapted to be removed when it is desired to remove the form from the frame of the machine.

Instead of providing friction surfaces 37 formed by transverse grooves; as heretofore described, the form may be provided at opposite sides of the central longitudinal slot 36 with friction surfaces formed by longitudinal strips 72 of rubber or other suitable material located at opposite sides of the slot 36 and preferably seated in recesses 73 in the upper faces of the form and projecting slightly above the upper surface of the form, as clearly illustrated in Fig. 7 of the drawings. When the form is equipped with friction surfaces of rubber or other material, feed rolls 74 having friction peripheries 75 are preferably used, as shown in Fig. 7. The friction surfaces 75 consist of bands or rings arranged on the feed rolls. The elasticity of the rubber bands forming the friction treads of the feed rolls will be ample for retaining the bands on the rolls, but any other suitable means may, of course, be employed for this purpose.

The hollow form is provided at the sides and at the top with ventilation openings 76 and 77 to prevent heating of the form and the fabric by the illuminating means. The

side ventilation openings 76 are arranged at both sides of the form at spaced points throughout substantially the entire length of the form, and the top openings 77, which are larger than the side openings, are located in the rear of the slot 36 and the friction surfaces at opposite sides thereof.

What is claimed is:

1. A machine for mending runs in fabrics, including a single needle provided with means for manipulating the threads of a run to close the latter, and manually operable means slideable at will by hand longitudinally of the run for feeding the threads thereof to the needle according to the gage of the fabric.

2. A machine for mending runs in fabrics, including a single needle provided with means for manipulating the threads of a run to close the latter, and a form constructed to permit a fabric to be stretched over it to support the threads of a run in position to be operated on by the needle, said form being slideable at will by hand longitudinally of the run to feed the threads to the needle according to the gage of the fabric.

3. A machine for mending runs in fabrics, including a single needle provided with means for manipulating the threads of a run to close the latter, and a form having a friction surface to support the threads of a run and provided at opposite sides thereof with portions adapted to be grasped by the operator for enabling the latter to simultaneously hold the fabric and the form and slide the form at will to feed the threads to the needle according to the gage of the fabric.

4. A machine for mending runs in fabrics, including a single needle provided with means for manipulating the threads of a run to close the latter, and a form having smooth portions adapted to be grasped by the operator simultaneously with a fabric supported by the form to enable the operator to tension the threads of the fabric and slide the form at the will of the operator to feed the threads to the needle without releasing the grip on the fabric.

5. A machine for mending runs in fabrics, including a single needle provided with means for manipulating the threads of a run to close the latter, and a manually slideable form provided with a needle receiving space and having thread-receiving surfaces at opposite sides of the said space for supporting the threads of a run said form being slideable backwardly and forwardly at the will of the operator.

6. A machine for mending runs in fabrics, including a single needle provided with means for manipulating the threads of a run to close the latter, and a manually slideable form provided with a needle receiving space

- and having thread-receiving surfaces at opposite sides of the said space for enabling the threads of a run to be spaced, said form being also provided with hand receiving side portions for enabling the form and fabric to be simultaneously grasped by the operator and the form and grasped fabric moved by the operator according to the gage of the material.
10. 7. A machine for mending runs in fabrics, including a single needle provided with means for manipulating the threads of a run to close the latter, and a manually slidable form provided with a needle receiving space and having thread-receiving friction surfaces at opposite sides of the said space for enabling the threads of a run to be tensioned and thereby spaced, said form being also provided with hand receiving side portions extending longitudinally of the form and adapted to permit the form and the fabric to be simultaneously grasped by the operator at various points along the form and moved by the operator at his will to cooperating position with relation to the needle according to the position of the threads of the run.
15. 8. A machine for mending runs in fabrics, including a single needle provided with means for manipulating the threads of a run to close the latter, and a manually slidable form provided with a needle receiving space and having thread-receiving surfaces at opposite sides of the said space for enabling the threads of a run to be spaced, said form being also provided with smooth longitudinal side portions located at opposite sides of the thread receiving surfaces to permit the form and the fabric to be simultaneously grasped by the operator at various points along the form to stretch the fabric, to tension the threads thereof, and to slide the form at the will of the operator to feed the threads to the needle.
20. 9. A machine for mending runs in fabrics, including a needle provided with means for manipulating the threads of a run to close the latter, manually operable means for supporting and feeding a fabric to the needle having a needle receiving opening, and illuminating means arranged interiorly of the supporting and feeding means and adapted to project rays of light through the needle receiving opening to show clearly the threads to be mended.
25. 10. A machine for mending runs in fabrics, including a needle provided with means for manipulating the threads of a run to close the latter, a relatively long hollow manually operable form arranged to support a fabric to be operated on by the needle and having a longitudinal opening therein, and illuminating means arranged interiorly of the hollow form and movable therewith and adapted to project rays of light through
- said opening to show clearly to the operator the threads to be mended.
11. A machine for mending runs in fabrics, including a needle provided with means for manipulating the threads of a run to close the latter, a hollow manually operable form adapted to support a fabric in position to be operated on by the needle and having a needle-receiving opening extending longitudinally of a run, and illuminating means arranged interiorly of the form and movable therewith and adapted to project rays of light through the said opening adjacent and to said needle to show clearly to the operator the threads to be mended. 75
12. A machine for mending runs in fabrics, including a single needle provided with means for manipulating the threads of a run to close the latter, a hollow, manually operable form arranged to support a fabric in position to be operated on by the needle and movable to present the threads of a run to the needle, and a light mounted within and carried by the form and adapted to project said rays of light through said opening to show clearly to the operator the threads to be mended. 80
13. A machine for mending runs in fabrics, including a single needle provided with means for manipulating the threads of a run to close the latter, a hollow manually operable form arranged to support a fabric in position to be operated on by a needle, a removable plug closing one end of the form, and an electric conduit carried by the plug and located within the hollow form and provided with a socket adapted to receive an electric light mounted within and carried by the form for illuminating the fabric to show clearly to the operator the threads to be mended. 95
14. A machine for mending runs in fabrics including a frame provided with horizontal guiding means, a power operated needle mounted on the frame and provided with means for manipulating the threads of a run for closing the latter, a manually operable form slidable at will by the operator along the guiding means and adapted to support the fabric in position to be operated on by the needle. 110
15. A machine for mending runs in fabrics including a frame provided with horizontal guide bars provided with antifriction means, a power actuated needle mounted on the frame and provided with means for manipulating the threads of a run for closing the latter, and a slidable form mounted between the guide bars and having grooves receiving the anti-friction means. 120
16. A machine for mending runs in fabrics including a frame provided with horizontal guide bars provided with antifriction means, a power actuated needle mounted on the frame and provided with means for ma- 125
- 130

- 5 nipulating the threads of a run for closing the latter, and a slidable form mounted between the guide bars and having grooves to receive the anti-friction means of the guide bars, the latter having their outer terminals bent inwardly into the grooves to prevent the fabric catching on the guide bars.
- 10 17. A machine for mending runs in fabrics including a single needle provided with means for manipulating the threads of a run for closing the latter, a manually operable slidable form arranged to support a fabric in position to be operated on by the needle, said form being provided below the fabric with a longitudinal slot, and a relatively 15 fixed stop projecting into the slot and forming an abutment adapted to be engaged by the end walls thereof for limiting the inward and outward movement of the form.
- 20 18. A machine for mending runs in fabrics including a frame having a hollow arm, a vertically reciprocating needle supported by the frame and provided with means for manipulating the threads of a run for closing the latter, a lever extending longitudinally of the arm and fulcrumed between its ends to form front and rear arms, the front arm actuating the needle, a cam associated with the rear arm for oscillating the lever, and a substantially horizontal manually operable form guided on the frame below the hollow arm and arranged to support a fabric in position to be operated on by the needle.
- 25 19. A machine for mending runs in fabrics, including a single needle provided with means for manipulating the threads of a run to close the latter, a manually operable hollow form arranged to support the fabric to be operated on by the needle, and illuminating means arranged interiorly of the hollow form and movable therewith and adapted to show clearly to the operator the threads to be mended, said form being provided with 30 ventilating openings for preventing heating of the form and the fabric by the illuminating means.
- 35 20. A machine for mending runs in fabrics, including a single needle provided with means for manipulating the threads of a run to close the latter, a hollow manually operable form arranged to support the fabric to be operated on by the needle, and illuminating means arranged interiorly of the hollow form and slidable with the form and adapted to show clearly to the operator the threads to be mended, said form being provided at opposite sides and at the rear portion of the top with ventilating openings 40 adapted to prevent heating of the form by the illuminating means.
- 45 21. A machine for mending runs in fabrics including a needle provided with means for manipulating the threads of a run to close the latter, means movable by hand for 45 supporting a fabric in position to be operated on by the needle, and having a needle receiving opening, and illuminating means arranged interiorly of the said movable supporting means and adapted to project the rays of light through said opening on to the fabric to show clearly the threads to be mended.
- 50 22. A machine for mending runs in fabrics including a mechanically operating needle provided with means for manipulating the threads of a run to close the latter, a hollow member for supporting a fabric in position to be operated on by the needle, and means whereby to manually impart relative movement to the needle and hollow member to present the threads of a run successively to the needle, and an electric lamp arranged interiorly of the said hollow member and extending longitudinally of the latter and adapted to project rays of light upon the fabric in the vicinity of the needle to show clearly the threads to be mended.
- 55 23. A method of repairing runs in knitted fabrics consisting in supporting the fabric, with the ladder-like threads of a run spaced apart, mechanically reciprocating a needle at intervals through the run to manipulate the threads to close the run, holding the fabric by hand at opposite sides of the needle, and tensioning the threads of the run by hand and while the fabric is thus tensioned sliding the fabric by hand to the needle.
- 60 24. A method of repairing runs in knitted fabrics consisting in supporting the fabric with the ladder-like threads of a run spaced apart, mechanically reciprocating a needle at intervals through the run to manipulate the threads thereof to close the run, holding the fabric by hand at opposite sides of the needle, tensioning the threads of the run by hand, and simultaneously sliding the fabric by hand to the needle.
- 65 25. A method of repairing runs in knitted fabrics consisting in supporting the fabric, mechanically reciprocating a needle at intervals through a run in the fabric to manipulate the threads thereof to close the run, holding the fabric by hand at opposite sides of the needle to tension the threads and thereby space the same, and simultaneously sliding the fabric by hand to the needle.
- 70 26. A method of repairing runs in knitted fabrics consisting in supporting a relatively large portion of the fabric on a form, mechanically reciprocating a needle at intervals through a run in the fabric to manipulate the threads thereof to close the run, tensioning the fabric by hand to space the ladder-like threads of a run substantially uniformly, and sliding the fabric by hand to the needle.
- 75 27. A method of repairing runs in knitted fabrics consisting in supporting a relatively 75

large portion of the fabric on a form, mechanically reciprocating a needle at intervals through a run in the fabric to manipulate the threads thereof to close the run,
5 holding the fabric by hand at opposite sides of the needle to tension the same, and thereby space the ladder-like threads of a run substantially uniformly, and simultaneously sliding the fabric by hand to the needle
10 without changing the position of the fabric on the form.

28. A device of the character described comprising a relatively long, narrow, hollow form to receive a stocking and support
15 a relatively long stretch of the stocking to be mended and provided with a relatively long narrow needle receiving slot, and having longitudinal recesses on opposite sides of said slot, and strips of pliable material
20 seated in said recesses and projecting slightly above said slot, the pliable strips having fine ribs and intervening grooves in their outer faces to prevent slipping of the stocking and to effect proper spacing of the cross
25 threads of the stocking.

29. A machine for mending runs in fabrics including means for manipulating the threads of a run to close the latter, means for supporting the fabric in position
30 to be operated on by the aforesaid means, one of said means being operable in a pre-determined definite position and the other means being slidably mounted for movement at the will of the operator by hand relative
35 to the means located in definite position, whereby to present the threads of the run successively to the means for closing the run.

In testimony whereof I have hereunto set
40 my hand, this 21 day of March, 1929.
JOSEPH S. PECKER.
